UNITED STATES PATENT OFFICE.

CHRISTIAN J. BUCK, OF GALLITZIN, PENNSYLVANIA.

INSULATED RAIL-JOINT.

SPECIFICATION forming part of Letters Patent No. 774,506, dated November 8, 1904.

Application filed May 12, 1904. Serial No. 207,714. (No model.)

To all whom it may concern:

Be it known that I, CHRISTIAN J. BUCK, a citizen of the United States of America, residing at Gallitzin, in the county of Cambria and State of Pennsylvania, have invented certain new and useful Improvements in Insulated Rail-Joints, of which the following is a specification, reference being had therein to the accompanying drawings.

10 My invention relates to certain new and useful improvements in rail-joints, and more particularly to that type of joint in which the meeting ends of the rails are insulated from themselves and from the connecting splice-bars, this form of rail-joint being employed on roads where extensive systems of electric signaling are used.

To this end the invention consists in the novel construction of the splice-bars and their arrangement with respect to the meeting ends of the rails which they connect, as will be more particularly described and claimed, reference being had to the accompanying drawings, forming a part of this specification, in

25 which—

Figure 1 is a perspective view of a rail-joint made in accordance with my invention, in which the various elements are shown assembled. Fig. 2 is a vertical section on the 30 line 2 2 of Fig. 1 looking in the direction of the arrow; and Fig. 3 is a perspective view of one of the members comprising the splice-bar, showing in detail the construction and contour thereof.

35 Like characters represent like parts throughout.

The splice-bar employed in my invention is of approximately square contour in cross-section for about two-thirds of its length, as indicated at 1, and then it gradually slopes off into an angle, as shown at 2. From the squared portion 1 and extending the length thereof I cut a member 3, the direction of the cut extending the length of the splice-bar until the 45 latter tapers toward its angular end, and then extending at right angles thereto, as shown at 6, until it reaches the inner side of the said splice-bar. The member 3 is cut with a beveled

face 4, which forms a bearing-surface for the corresponding beveled inner face 5 of the 50 squared portion 1.

In assembling the splice-bars upon the ends of the rails I place insulating-strips 7, of any suitable material, between the beveled faces 4 and 5 of the members 3 and 1, respectively, 55 and then bend the said strips, as at 8 in Fig. 1, to conform to the angle 6 of the inner face of the squared end 1, as it is when the member 3 has been cut therefrom. The splice-bar upon the other side has its members put 60 together in the same manner. I then insulate the ends of the rails from one another by means of an end strip 9. In joining the meeting ends of the rails I arrange the splice-bar (arbitrarily termed A) with its squared end adjacent the 65 rail a, and the splice-bar B with its squared end adjacent the rail b, so that the squared end of one bar, A, on one side of the rail is adjacent the angular end of the other bar, B, on the other side of the same rail, this arrangement being necessary to completely insulate 70 the rails from the splice-bar and being a distinctive feature of my invention. It is also advantageous in preserving an even weight and balance throughout the structure. It is 75 advantageous in assembling the members of the joint that the ends 6 of the squared portion 1, formed by cutting away the members 3, shall in each splice-bar be adjacent the point where the ends of the rails meet, so that when 80 the insulating-strips 7 are inserted the bent portions 8 between the members 1 and 3 thereof in each splice-bar will be adjacent the end strip 9. The various elements having been properly arranged I connect the rails and the 85 splice-bars by bolts 10, passing through apertures 11 in the splice-bars, the said bolts having their threaded ends secured adjacent the squared portion 1 by nuts 12, insulated by bushings 13 in the usual manner. Thus 90 the ends of the rail are insulated from one another by the insulation 9 and from the splice-bars by the insulation 7, so that there are no points where the iron is in contact, and all danger of completing a circuit is obviated.

95 The outside members of each splice-bar are

provided with notches 2' 3' to receive spikes of the usual form to engage in the cross-ties. (Not shown.)

It is obvious that several minor changes may 5 be made without departing from the spirit or scope of my invention.

Having thus fully described my invention, I claim—

1. In a rail-joint the combination with the 10 meeting ends of the rails having a strip of insulation interposed therebetween, of a pair of splice-bars insulated from the rails, each of said splice-bars having an enlarged end, one of said splice-bars being located on each side 15 of the rails and connected to the adjacent splice-bar by bolts passing through the rails.

2. In a rail-joint the combination with the meeting ends of the rails, having a strip of insulation interposed therebetween, of a splice-bar, said splice-bar being formed in a plurality of separable sections and being insulated 20 from the rails which it connects.

3. A splice-bar for rail-joints having a portion 25 of its body rectangular in cross-section and consisting of two members, one of said members being cut from the squared portion of the said splice-bar and a strip of insulation interposed between the said members, substantially as described.

30 4. A splice-bar for rail-joints having an angular smaller end and a squared larger end, said splice-bar being formed of two members, one of said members being cut from the said squared end, the surface of the said end from 35 which the said member has been cut being beveled and the adjacent surface of the said member being beveled and having a strip of insulation interposed between the said beveled surfaces substantially as described.

40 5. In a rail-joint the combination with the meeting ends of the rails having an end strip of insulation interposed therebetween, of a splice-bar having a squared end and comprising 45 two members, one of said members being cut from the said squared end, the said cut-away member having its end extending at a right angle to its side thereby leaving the surface of the splice-bar from which the said member has been cut approximately L-shaped, 50 and a strip of insulation interposed between the two members and having its end adjacent the end of the cut-away member and the end of the squared portion of the splice-bar bent at right angles to that portion of the said strip 55 between the adjacent faces of the said members of the splice-bar.

6. In a rail-joint, the combination with the meeting ends of the rails having an end strip of insulation interposed therebetween, of a 60 splice-bar having a squared end and comprising two members, one of said members being cut from the said squared end, the surface of the said squared end where the member has been cut away and the adjacent surface of the

said cut-away member being beveled, the said 65 cut-away member having its end extending at a right angle to its beveled side thereby leaving the surface of the splice-bar from which the said member has been cut approximately L-shaped, and a strip of insulation interposed 70 between the beveled surfaces of the two members and having its end adjacent the adjacent ends of the cut-away member and of the squared portion of the splice-bar bent at a right angle to that portion of the said strip 75 between the beveled faces of the adjacent members of the splice-bar.

7. In a rail-joint, the combination with the meeting ends of the rails, having a strip of insulation interposed therebetween, of a pair 80 of splice-bars insulated from the rails, said splice-bars having one end larger than the other, one of said splice-bars being located on one side of the meeting-rails and the other of said splice-bars being located on the other side of the meeting-rails, the splice-bars being so positioned with relation to one another that the smaller end of one splice-bar is adjacent the larger end of the other splice-bar, the said splice-bars being connected by bolts 85 passing through the rails.

8. In a rail-joint the combination with the meeting ends of the rails having an end strip of insulation interposed therebetween, of a 90 pair of splice-bars, said splice-bars having one end larger than the other, one of said splice-bars being located on one side of the meeting-rails and the other of said splice-bars being located on the other side of the meeting-rails, the larger ends of the splice-bars being 95 insulated from the rail to a point adjacent the said end strip of insulation interposed between the meeting ends of the rails, the enlarged end of one splice-bar being adjacent the smaller end of the other splice-bar, the 100 splice-bars being connected by bolts passing through the rails.

9. In a rail-joint, the combination with the meeting ends of the rails having an end strip of insulation interposed therebetween, of a 105 pair of splice-bars having one of their ends larger than the other, the enlarged end being formed in detachable sections, and having a strip of insulation interposed between the said sections, said strip of insulation terminating adjacent the end strip of insulation between the meeting-rails, the enlarged end of one splice-bar on one side of the rail being adjacent the smaller end of the corresponding 110 splice-bar on the other side of the rail, the 115 splice-bars being connected by bolts passing through the rails.

In testimony whereof I affix my signature in the presence of two witnesses.

CHRISTIAN J. BUCK.
